(57) **CLAIM**

The ornamental design for a waveguide assisted strip antenna for RFID tags, as shown and described.

DESCRIPTION

FIG. 1 is a top plan view of a waveguide assisted strip antenna for RFID tags showing my new design; and,

FIG. 2 is a top plan view thereof in use with an RFID chip.

The broken line showing of an RFID chip in FIG. 2 illustrates environment only and forms no part of the claimed design. The solid black areas constitute the entirety of the claimed design.
